(57) **CLAIM**

The ornamental design for a general purpose engine, as shown and described.

DESCRIPTION

FIG. 1 is a front view of a general purpose engine showing our design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is an upper left front perspective view thereof;

FIG. 8 is an upper right rear perspective view thereof;

FIG. 9 is an enlarged upper left front perspective view of a portion thereof; and,

FIG. 10 is an enlarged upper right rear perspective view of a portion thereof.

The portions of FIGS. 1-10 shown in coarse dot pattern and outlined in dashed lines form no part of the claimed design.
